APPARATUS FOR USE IN TESTING
SOLUTIONS

Martin W. Baden, Winfield, Kans.

Application September 4, 1931, Serial No. 561,297

7 Claims. (Cl. 219—38)

This invention relates to improvements in methods and apparatus for the rapid evaporation of aqueous or volatile solutions, etc.

In order that the invention may be clearly understood, reference may first be made to the prior methods employed in making water analyses and the corrosion and gum test of gasoline and naphtha. In making water analyses, the following method is used in most laboratories. The sample is obtained in a one-half or one gallon bottle, and the analyses are made of the filtered samples, the results being reported in either parts per million, or grains per gallon. For example, to ascertain the total solids, a 50 cc. sample of the water is placed in a dish which in turn is put in a steam bath until the sample is evaporated to dryness, and then the dish is put over to dry. This method requires about 4 to 6 hours for the evaporation on the steam bath, and then an additional two hours in an oven at about 180° F.; making a total of about six to eight hours for analyzing a 50 cc. sample. In accordance with my invention, superior results can be obtained in making such an analysis in about one or two hours.

Heretofore, in making corrosion and gum tests of gasoline and naphtha, 100 ccs. of gasoline or naphtha are placed in a freshly polished hemispherical dish of spun copper, approximately 3½ inches in diameter, and then this dish is placed in a steam bath until all volatile portions of the hydrocarbons have disappeared. If the sample contains any dissolved elementary sulphur, the bottom of the dish will be blackened, and if it contains an undesirable gum forming content there will be a weighable amount of gum deposited on the dish. Such a proposed method has never been accepted as absolutely standard, as the steam contaminates the gum with moisture, and the copper dish oxidizes on the exterior, which imparts an added weight to the dish. Consequently, it is very difficult to ever make an accurate check, due to the above causes.

In my United States patent application Serial No. 449,339, filed May 2nd, 1930, I have disclosed a method and apparatus for overcoming these difficulties, and this is done mainly by eliminating the steam bath and procuring the evaporation by directly heating the contents of the test dish from a point above the same.

The primary purpose of the present invention is to improve the process and apparatus of said application, mainly by employing the heater to heat a coil through which air is forced, and then directing this heated air into the sample in the

test dish. By using such a coil, I not only obtain heat units directly from the heater on the sample to be evaporated, (dehydrated), but also secure the evaporating effect of hot or warm air. With regard to the use of air for gum test, attention is directed to an article in the Oil and Gas Journal of July 16, 1931.

With the foregoing objects outlined and with other objects in view which will appear as the description proceeds, the invention consists in the novel features hereinafter described in detail, illustrated in the accompanying drawing, and more particularly pointed out in the appended claims.

In the drawing,

Fig. 1 is a side elevation of one form of apparatus which I have devised for my purpose.

Fig. 2 is a horizontal sectional view of the same, and

Fig. 3 is a vertical sectional view of a portion of the same.

For the purpose of disclosing the present invention, I have selected the electric heating device and method of my prior application, but I desire to be understood that in the present invention, I may also use a gas burner and plate or the like, as disclosed in said application, instead of an electric heater.

In the drawing, 4 indicates any suitable base from which rises a post 5 which supports a vertically adjustable bracket 6 that may be secured at any desired height along the post by a thumb screw 7. The bracket has a laterally extending arm 8 which carries an extension 9 arranged at right angles thereto, and this extension in turn supports a depending vertical rod 10.

A dish supporting bracket 11 is adjustably secured on the rod by means of a thumb screw 12, and carries the dish 13 in which the sample is placed. If the device is to be used in testing gasoline or naphtha, such dish is preferably hemispherical in shape and formed of spun copper.

Adjustably mounted on the rod 10 above the bracket 11, is a heater supporting bracket 14 which may be held at various elevations relatively to the dish by means of a thumb screw 15.

16 designates any suitable form of heating device from which the heat may radiate downwardly into the dish 13, and for the purpose of disclosing the present invention, the heater is shown as of the electric type, and includes an internal resistance coil 17 receiving current from the wires 18 which may lead to any suitable source of electricity. A handle 19 on the casing of the

heater may be employed in raising or lowering the same after the screw 15 is loosened.

In the present invention, an air coil 20 is associated with the heater, and I prefer to arrange this coil on the exterior of the heater and to make the casing of the latter of heat conducting material, so that heat radiated horizontally from the heater will heat the air which is forced into the coil through its inlet 21 by any suitable means, such as a pump (not shown). The outlet of the coil is shown at 22, and it is in the form of a nozzle positioned at the center of the bottom of the heater, so that the heated air discharged from the coil will be directed downwardly into the central portion of the dish 13.

I prefer to arrange a valve 23 on the coil to control the volume of air fed to the dish.

In making a water analysis with this apparatus, a filtered sample of 50 ccs. of water for example, is placed in the dish 13, and the latter is arranged on the bracket 11. Then the heater 16 is lowered to a desired elevation relatively to the dish, and if the current is on, the heat radiated downwardly into the dish will evaporate the contents of the dish to dryness in about one hour. If a flame heated plate is employed instead of the electric heater, the sample may be dehydrated in about two hours.

If the apparatus is used for a corrosion and gum test of gasoline or naphtha, a 100 cc. sample of such hydrocarbons can be placed in the dish, and then the heater may be employed to radiate heat downwardly into the sample for evaporating the same to dryness. If the gasoline contains any dissolved elementary sulphur, the bottom of the copper dish will be blackened, and if it has an undesirable gum forming content, there will be a weighable amount of gum deposited on the dish, and these results will be obtained without any oxidation on the outside of the dish, or any contamination of the contents due to moisture or oxidation.

In analyzing water, it is unnecessary to use the air coil, but in the gum test, I, of course, force air through the coil and then direct this heated air into the dish.

While I have disclosed what I prefer to be a preferred embodiment of the invention in such manner that the same may be readily understood by those skilled in the art, I am aware that changes may be made in the details without departing from the spirit of the invention, as expressed in the claims.

What I claim and desire to secure by Letters Patent is:

1. In an apparatus of the character described, an open top dish to contain a solution to be evaporated, heat generating means arranged entirely above the dish and adapted to direct heat into the dish from above the latter, and means heated by the heat generating means for introducing a stream of air into the dish from a point above the latter, said heat generating means and the top of the dish being spaced apart to allow vapors to freely escape between them.

2. In an apparatus of the character described,

an open top dish to contain a solution to be evaporated, heat generating means arranged above the dish and adapted to direct heat into the dish from above the latter, means for introducing a stream of air into the dish from a point above the latter, and means for raising and lowering the dish relatively to said heat generating means.

3. In an apparatus of the character described, an open top dish to contain a solution to be evaporated, heat generating means arranged above the dish and adapted to direct heat into the dish from above the latter, means for introducing a stream of air into the dish from a point above the latter, and means for adjustably supporting the heat generating means at various elevations relatively to said dish.

4. In an apparatus of the character described, an open top dish to contain a solution to be evaporated, heat generating means arranged above the dish and adapted to direct heat into the dish from above the latter, and means for introducing a stream of air into the dish from a point above the latter, the means for introducing air into the dish including a coil associated with the heat generating means and heated by the latter for heating the air flowing through the coil.

5. In an apparatus of the character described, an open top dish to contain a solution to be evaporated, heat generating means arranged above the dish and adapted to direct heat into the dish from above the latter, means for introducing a stream of air into the dish from a point above the latter, the means for introducing air into the dish including a coil associated with the heat generating means and heated by the latter for heating the air flowing through the coil.

6. In an apparatus of the character described, a base, a post rising from the base, a depending rod adjustably supported by the post, an open top dish to contain a solution to be evaporated adjustably supported by the rod, heat generating means arranged above the dish and adapted to direct heat into the dish from above the latter, means for adjustably supporting the heat generating means on said rod, and means supported by the heat generating means for introducing a stream of air into the dish from a point above the latter.

7. An apparatus of the character described comprising an open top dish to contain a solution to be evaporated, heat generating means arranged above the dish and adapted to direct heat into the dish from above the latter, said means being spaced from the top of the dish to allow the free escape of vapors between them, a nozzle arranged below the heat generating means for introducing a stream of air into the dish from a point above the latter, and an air passageway heated by the heat generating means and terminating in said nozzle.
